UNITED STATES PATENT OFFICE.

GEORGE HENRY FIRTH, FRANK HOLDSWORTH BENTHAM, AND JOHN HENRY STOTT, OF BRADFORD, ENGLAND.

INCANDESCENT GAS-BURNER.

SPECIFICATION forming part of Letters Patent No. 650,459, dated May 29, 1900.

Application filed June 26, 1899. Serial No. 721,972. (No model.)

To all whom it may concern:

Be it known that we, GEORGE HENRY FIRTH, engineer, residing at 35 Carlisle Terrace, FRANK HOLDSWORTH BENTHAM, machinist, 5 residing at 16 Laisteridge Lane, and JOHN HENRY STOTT, dyer, residing at 17 Cranbourne road, Chellow Dean, Bradford, in the county of York, England, subjects of the Queen of Great Britain and Ireland, have invented certain Improvements in or in Connection with 10 Incandescent Gas-Burners, of which the following is a specification.

This invention relates to improvements in or in connection with burners and supports for incandescent gas-lighting, such as are in use 15 at the present time, our object being to prevent vibratory shocks from injuring or destroying the delicate mantles used in this form of gas-lighting.

Our invention will be fully described with 20 reference to the accompanying drawings, in which—

Figure 1 is a vertical section of a burner fitted with our improvements, and Fig. 2 an 25 elevation of the Bunsen-tube arrangement fitted with some of the improved parts.

From the drawings it will be seen that in carrying out our invention we make use of the ordinary form of Bunsen tube A as used 30 for the incandescent gas-burners commonly in vogue at the present time; but in order to secure the mantles from vibratory shocks that would prematurely destroy them we separate the cap B, which supports the mantle and rod 35 and which is usually fixed on the Bunsen tube, and fit it onto the top of another tube C of larger dimensions than the Bunsen tube and which is made to inclose the latter, but without contact other than that made by a loose 40 plate or tube, as described later. The said free tube C is made to hang by means of an internal flange D at its upper end upon the expanded end of a conical spring E, vertically fixed, the smaller end of which is passed 45 over the Bunsen tube and rests on an adjustable supporting-ring F on the Bunsen tube. Over the exterior of the hanging tube C we slip a balance-weight G of suitable dimensions, which by its inertia prevents a too-sudden 50 movement when effected by shocks and

which rests on an external flange H at the lower end of the said tube.

When the free or swinging portion of the burner is suspended on an internal spring E, such as we have described above, we fix upon 55 the upper end of the Bunsen tube, which projects within the spring, an adjustable ring J, shaped on its exterior in conformity with the taper of the spring E and which can be raised or lowered by being screwed, as indicated in 60 Fig. 2, so as to come more or less in contact with the spring, according to the amplitude of the lateral oscillations that may be set up in the said free parts, whereby a too-violent movement in that direction can by this means 65 be prevented.

In a compact arrangement of burner with gauze cap, such as we have described and shown in the drawings herewith, we find it necessary to close up the intervening space 70 between the free tube C and the Bunsen supply-tube A because of the liability of the combustible to escape and light back at this point, especially if the combustible is to be used increased in pressure. To seal this effectually and at the same time allow the swinging part a universal freedom of movement, we insert a loose conical tube K, of metal or other refractory substance, between the free tube C and the Bunsen tube A in 80 such a way that its upper and wider end has a sliding contact with the inner surface of the free tube C, while its lower and narrower end has sliding contact on the Bunsen tube A, by which means we obtain the necessary 85 freedom of movement, while at the same time we get an inclosed chamber effectually sealed against the dangerous or wasteful passage of air or gas and an enlarged mixing-chamber for the combustible from the Bunsen or supply tube, whether the pressure be normal or 90 otherwise.

What we claim as our invention, and desire to secure by Letters Patent, is—

1. The combination of an incandescent gas- 95 burner separate from the Bunsen tube or supply-pipe and supported by springs or other resilient means, an adjustable nut or ring for checking lateral movement, and a conical sealing-tube, all arranged as herein described. 100

2. In a burner for incandescent gas-lighting the combination with a spring located in the Bunsen tube and supporting the burner and mantle of an adjustable nut or ring on the Bunsen tube or supply-pipe for checking lateral movement of the said supporting-spring substantially as described.
3. In burners for incandescent gas-lighting the combination of a loose conical sealing-tube free to move in the intervening space between the loose and fixed parts of the burner and a tube surrounding said sealing-tube, both forming a mixing-chamber substantially as and for the purposes described.
4. In burners for incandescent gas-lighting the combination with Bunsen tube A and mantle, of a cap B removably mounted on a tubular chamber C, tubular chamber C with flanges D and H, spring E supporting chamber C, weight G resting on flange H of chamber C, conical sealing-tube loosely mounted on tube A and engaging therewith at its

lower end and with interior of chamber C at its upper end, collar F adjustably mounted on tube A and supporting spring E, and conical nut or ring J also adjustably mounted on tube A to regulate lateral movement of spring E substantially as described. 25

5. In burners for incandescent gas-lighting the combination with tube A, of collar F adjustably mounted thereon, spring E resting on collar F and conical nut or ring J also adjustably mounted on tube A to regulate lateral movement of spring E substantially as described. 30

In witness whereof we have set our hands in the presence of two witnesses.

GEORGE HENRY FIRTH.

FRANK HOLDSWORTH BENTHAM.

JOHN HENRY STOTT.
